UNITED STATES PATENT OFFICE.

FRANK FEUERSTEIN, OF WILLIAMSVILLE, NEW YORK.

POULTRY-FEEDING DEVICE.

1,142,687.

Specification of Letters Patent. Patented June 8, 1915.

Application filed February 13, 1914. Serial No. 818,546.

To all whom it may concern:

Be it known that I, FRANK FEUERSTEIN, a citizen of the United States, residing at Williamsville, in the county of Erie and State of New York, have invented new and useful Improvements in Poultry-Feeding Devices, of which the following is a specification.

This invention relates to poultry feeding devices, and it has for its object to produce a device of simple and inexpensive construction including a food receptacle having a swinging door, latch means for retaining the door in a closed position, and means for releasing the latch at a predetermined time, thereby permitting the food to escape and drop on the ground or into a receptacle provided for its reception and which will be accessible to the poultry to be fed.

20 A further object of the invention is to produce a simple and efficient device of the character described in which the trigger mechanism may be operated or actuated by a timing device consisting of an ordinary alarm clock.

With these and other ends in view which will readily appear as the nature of the invention is better understood, the same consists in the improved construction and novel 30 arrangement and combination of parts which will be hereinafter fully described and particularly pointed out in the claims.

In the accompanying drawing has been illustrated a simple and preferred form of 35 the invention, it being, however, understood that no limitation is necessarily made to the precise structural details therein exhibited, but that changes, alterations and modifications within the scope of the claims may be 40 resorted to when desired.

In the drawing, Figure 1 is a perspective view of a device constructed in accordance with the invention. Fig. 2 is a rear elevation of the same. Fig. 3 is a vertical sectional view taken on the line 3—3 in Fig. 2. Fig. 4 is a sectional detail view taken on the line 4—4 in Fig. 2.

Corresponding parts in the several figures are denoted by like characters of reference. 50 Referring to the drawing, A designates a hopper shaped casing 10 supported on legs or uprights 15 and having a hinged lid 16 and a hinged bottom member 17, the latter being adapted to be retained in closed 55 position by means of a hook-shaped latch member or lever 18 pivoted on one side of

the casing and adapted to engage a pin 19 projecting from one edge of the bottom member 17. Extending transversely through the lever or latch member 18 or otherwise connected therewith substantially at right angles thereto is a trigger rod having long and short arms designated, respectively, by 20 and 21. The long arm 20 extends beyond one end of the casing.

Mounted or secured on the end of the casing is a box 23 in which an ordinary alarm clock 24 is accommodated, said box being provided with front and rear doors 25, 26, through which the clock is accessible for the purpose of setting and winding the same, the front door having a transparent pane 27 through which the clock face may be observed. The alarm post 28 of the clock is provided with a disk 30 having a wrist pin 31 adapted to engage above the long arm 20 of the trigger rod which extends through a slot 30' in one side of the box so as to be capable of engaging the wrist pin 31. The short arm 21 of said rod carries an adjustable weight 32, the gravity of which tends to maintain the hook lever or catch member 18 in engagement with the pin 19 to secure the bottom member of the receptacle in closed position.

It is preferred to make the lid or cover 16 of arcuate, approximately semi-circular shape in cross section. Said lid or cover is, moreover, provided adjacent to the ends thereof with uprights 33 supporting a longitudinally disposed wire 34, said wire being positioned some three or four inches above the lid so as to prevent the poultry from roosting on said lid. It is also preferred to extend one edge of the lid beyond the side of the box or hopper, as indicated at 35, to form a cornice that will protect the trigger rod.

In the operation of this device, the alarm clock is set to the hour at which it is desired to trip the device, and the alarm is then wound, care being taken to leave the wrist pin 31 at or near the highest point above the axis of the winding post. The bottom member 17 is now closed, it being maintained in a closed position by the catch member 18 which, under the influence of the weight 21 will be held in engagement therewith. The desired quantity of feed is now placed in the box through the opening obstructed by the cover member 16. It is evident that by adjusting the catch the free end of the long

arm 20 of the trigger rod will be moved upward into engagement with the wrist pin 31. When, at the predetermined hour, the alarm is released, the rotation of the disk 30 will 5 cause the wrist pin to move the arm 20 downward, thereby tilting the catch member 18 and releasing the pin 19, thus permitting the door to swing open and the contents of the hopper to escape.

10 It will here be noted that the weight 32 is to be adjusted on the arm 21 of the trip lever in accordance with the amount of feed that is placed in the box. When the box is practically filled, the weight exerted on the 15 member 17 is obviously greater than when a small quantity of feed is placed in the box; hence when the box is filled to its capacity, the weight 32 should be moved in the direction of the latch member 18, while when 20 but a small quantity of feed is placed in the box, the weight should be moved outward from the latch member so as to exert a greater tension on the lever. Thus, when the box is but partly filled the gravity of the 25 weight will have to be overcome in addition to the friction caused between the latch member 18 and the pin 19 by the weight of the load in order to open the box to release the contents. The weight 32 thus constitutes 30 a safety device which will guard against the release of the latch by accident or by the pecking of the fowls thereagainst, it being possible to gage the adjustment of said safety device so accurately that the power 35 exerted by the alarm clock will at all times be sufficient to actuate the latch for the purpose of releasing the contents of the box.

It will be seen that I have produced an 40 extremely simple and thoroughly effective automatic poultry feeding device which may be actuated at any hour previously determined. I desire to state that within the 45 scope of the invention, the hopper-shaped receptacle may be divided longitudinally and provided with a bottom door for each compartment, in which event an alarm clock and actuating mechanism may be provided at each end of the device, thus enabling the device to be adapted for two separate feed-

ings, but inasmuch as this would involve 50 mere duplication of parts, it is not considered necessary to particularly illustrate the same.

Having thus described the invention, what is claimed as new, is:—

1. In a device of the class described, a hopper-shaped casing including a hinged bottom member, the latter having a pin projecting at the free edge thereof, a lever pivoted on a side member of the casing and 60 having a hook engaging the pin, a trigger rod connected with the lever substantially at right angles thereto and having long and short arms, a weight adjustable on the short arm and tending to maintain the hook of the 65 catch lever in engagement with the pin of the bottom member, and an alarm clock supported in proximity to the casing and having an alarm post carrying a disk provided with a wrist pin projecting in the path of 70 the long arm of the trigger rod.

2. In a device of the class described, a hopper-shaped casing having a hinged bottom member, the latter having a pin extending 75 from the free edge thereof, a box mounted on one end of the casing and having a slot in one side thereof, an alarm clock contained in said box and having a projecting alarm post carrying a disk having a wrist pin, a catch lever pivoted on one side of the 80 casing and having a hook engaging the pin extending from the bottom member, a trigger rod connected with the catch lever at right angles thereto and having a long and a short arm, the long arm being guided 85 through the slot in the side of the box beneath the wrist pin, and a weight adjustable on the short arm of the trigger rod and serving to maintain the catch lever in engagement with the pin of the bottom mem- 90 ber.

In testimony whereof I affix my signature in presence of two witnesses.

FRANK FEUERSTEIN.
